DENTAL LIGHT OR SIMILAR ARTICLE

Daryl D. Sullivan, Corning, N.Y., Arthur L. Jones, 5001
Milford Road, and Eugene J. Neal, Jr., 3613 Trent St.,
both of Charlotte 9, N.C.; said Sullivan assignor to
Corning Glass Works, Corning, N.Y., a corporation of
New York

Filed May 17, 1963, Ser. No. 74,934

Term of patent 14 years

(Cl. D48—20)

FIGURE 1 is a front perspective view of a dental light or similar article showing our new design;

FIGURE 2 is a rear perspective view of the dental light or similar article;

FIGURE 3 is a top plan view of the dental light or similar article;

FIGURE 4 is a side elevational view of the dental light or similar article, with the holder therefor shown in dotted lines being broken away; and

FIGURE 5 is a cross sectional view of the dental light taken substantially along the line 5-5 of FIGURE 1.

The dominant features of the design reside in those portions shown in full lines on the drawings.

We claim:

The ornamental design for a dental light or similar article, substantially as shown and described.
